(57) **CLAIM**

The ornamental design for an outlet cover with cord wrap as shown and described.

DESCRIPTION

FIG. 1 is a top plan view showing the new, original, and ornamental design of an outlet cover with cord wrap;

FIG. 2 is bottom plan view thereof;

FIG. 3 is a left elevation view thereof;

FIG. 4 is a right elevation view thereof;

FIG. 5 is a front elevation view thereof;

FIG. 6 is a rear elevation view thereof; and

FIG. 7 is a perspective view thereof.

The broken lines shown in the drawings are for the purpose of illustrating portions of the article that form no part of the claimed design.

1 Claim, 5 Drawing Sheets
